UNITED STATES PATENT OFFICE.

BENGT M. W. HANSON, OF HARTFORD, CONNECTICUT.

METAL-WORKING MACHINE.

Application filed June 15, 1921. Serial No. 477,660.

To all whom it may concern:

Be it known that I, BENGT M. W. HANSON, a citizen of the United States, and a resident of Hartford, county of Hartford, State of Connecticut, have invented certain new and useful Improvements in Metal-Working Machines, of which the following is a specification.

This invention relates to improvements in metal working machines. The various features of the present invention will be described with reference to their use in the particular machine now selected for the purpose of illustration which is a machine for centering work to be turned. I desire it to be clearly understood, however, that the present invention is susceptible of other embodiment and that the terms used are merely terms of description and not in any sense terms of limitation. It will be obvious that many features of construction are susceptible of modification to suit different requirements, without departing from the spirit of the invention.

The object of this invention is to provide a machine of the character described having various features of novelty and advantage, and which is particularly characterized by its accuracy and efficiency in operation.

In the accompanying drawings:

Fig. 1 is a side view of the complete machine.

Fig. 1^a is a detail view of the chuck operating lever, looking in the direction of arrow 35 1^a in Fig. 1.

Fig. 2 is a top view, partly in section, of the head stock.

Fig. 3 is a side view of the head stock, a cover plate of the casing being removed.

Fig. 4 is a central vertical sectional view taken longitudinally through the chuck spindle, that is substantially on line 4—4 of Fig. 2.

Fig. 5 is a front end view of the head stock, parts being shown in section.

Fig. 6 is a top plan view of the tail stock with a cover plate removed, the operating lever which is carried by this cover, being shown in dotted lines, and parts being in section.

Fig. 7 is a side view of the tail stock with parts broken away.

Fig. 8 is a front end view thereof with parts broken away.

Fig. 9 is a plan view of work holding lever 161 and associated parts.

Fig. 10 is a detail view taken on line 10—10 of Fig. 8 and illustrates, in section, the forward end of one of the tool holders.

Fig. 11 is a detail sectional view taken on line 11—11 of Fig. 6 and illustrates the means for longitudinally adjusting the hand operated spindle of the work rest positioned on the tail stock.

Briefly, the machine disclosed in the present embodiment comprises a bed or base A on one end of which is fixed a head stock B provided with a chuck and means for approximately positioning one end of the work so that it may be readily gripped by the 70 chuck; and on the other end of the bed is slidably mounted a tail stock C provided with means for very accurately positioning and rotatably supporting the other end of the work relative to certain tools carried by 75 the tail stock. In the present instance, one of these tools comprises a combined drill and countersink and the other a shaving tool, and these tools are adapted to be successively brought into proper relation to the chuck, so 80 that the drill may first form a hole in the work and then that hole may be trued up by the shaving.

The detailed construction of the head stock will now be described. Referring particularly to Figs. 4 and 5, mounted within suitable bearings 10 in the head stock casting 11 is a spindle 12 on the forward end of which is fixed a chuck having a head 13 in which is slidably mounted a pair of jaw blocks 14, the jaws 15 of which are stepped to accommodate pieces of work of different sizes. 16 designates a screw having left and right handed thread portions in threaded engagement with the respective jaw blocks 14 90 so that when this screw is rotated the blocks move to and from each other to respectively chuck and unchuck, depending on the direction in which the screw is rotated. The screw 16 is rotatably supported at its ends 100 by bearing members 17 which are preferably in the form of screws to permit of such adjustment of the jaw blocks as to bring them concentric with the axis of the spindle 12. For the purpose of rotating the screw 16, it 105 is provided with a pinion 18 with which meshes a rack 19 on a bar 22 extending through and slidably mounted in the spindle. This bar carries on its outer end a collar 23 in the groove of which engages rollers 24 on 110 the yoke end of an operating lever 25 pivoted as at 26 (Fig. 2). On the spindle 12 is a

loose pulley 27 and a fixed pulley 28, to receive a belt 29 adapted to be thrown from one of the pulleys to another by the shipper 30 carried by a rod 32 slidably mounted in 5 suitable bearings in the casing 11. The shipper 30 is moved in a direction to throw the belt 29 from the loose pulley onto the fixed pulley 28, through a bell crank 33 and a connecting rod 34, by the foot treadle 35.

10 For convenience in operation of the machine, and particularly for the purpose of reducing the number of movements necessary on the part of the operator, provision is had whereby the chuck may be unchucked 15 and the power thrown off of the spindle simultaneously by the single operation of throwing the lever 25. The manner in which this is brought about will be most readily understood with reference to Figs. 20 2 and 3. The rod 32, together with the shipper 30 carried thereby, is normally urged in a direction to throw the belt onto the loose pulley 27 by a compression spring 36. Pivoted within the head stock casing, as at 25 37, is a lever 38 one of the arms of which carries a catch 39 with which cooperates a latch 42 having a slight vertical movement in the collar 43 fixed to the rod 32. It will be seen that when the shipper is moved to throw the 30 power on, the latch 42 will have locking engagement with the catch 39 and hold the shipper in "on" position against the compression of the spring 36. Slidably mounted beneath the rod 32 is a rod 44 having a fixed 35 abutment 45 and a spring pressed abutment 46 between which is interposed a projection or finger 47 depending from the lever 38. Pivotedly connected to the rod 44 is a rod 48 which extends through a block 49 pivoted as 40 at 52 to the lever 25. Within a bore in the block 49 and engaging against the rod 48 is a shoe 53 behind which is a compression spring 54. The force of this spring is such that when the lever 25 is thrown the tendency 45 is to longitudinally move the rod 48 and the parts associated therewith.

Now, assuming that the power is on (in which case the latch 42 is cooperating with the catch 39), and also that the operating lever 25 is in the position shown in Figs. 50 2 and 3 (in which case the chuck jaws are gripping the work), when the lever is thrown to the right, the bar 22 will be shifted outwardly causing the jaw blocks 55 to move apart and release the work and, at the same time, the rods 48 and 44 will be moved to the right, and due to the interengagement of the collar 45 and the finger 47, the lever 38 will be rocked to withdraw the 60 catch 39 from the latch 42 whereupon, under the influence of the spring 36, the shipper will be moved to the left, thus shifting the belt 29 onto the loose pulley 27 so that the power is thrown off.

65 In some instances, it may be desirable to

unchuck without throwing the power off, and therefore the following means are provided for rendering the connection between the lever 25 and the catch 39 inactive, at will. 57 designates a cam fixed to a stud 58 journaled in a cover plate 59 and having at its outer end a handle 60 whereby it may be turned. The periphery of this cam has a flattened portion 61 and cooperates with an abutment 62 on the rod 44. It will be seen that when the flattened portion 61 faces the abutment 62, as shown in Fig. 3, the rod 44 will be moved when the lever 25 is thrown in a direction to unchuck. When the cam is turned to bring the circular portion 80 thereof against the abutment 62, the rod 44 is held against reciprocation and the friction shoe 53 will merely slide along the rod 48 when the lever 25 is thrown, and the belt will not be shifted.

It is further desirable, in some instances, to throw the power off without unchucking, and to this end there is provided on the lever 38 a handle 64 extending through an opening 65 in the cover plate 59. The lever 38 may be manually rocked by this handle to lower the catch 39 out of engagement with the latch 42 whereupon the spring 36 will throw the shipper 30 in a direction to shift the belt onto the loose pulley 27.

For the purpose of supporting the work in such position that it may be gripped by the chuck jaws, a work rest 68 and means for approximately adjusting the same in accordance with the diameter of the work, are provided. The work rest 68 comprises a vertically adjustable plate having a V at its upper end. Secured to the inner face of this plate is a T-block 69 guided by vertical ways 70 in the end plate 71 of the head stock casing. The inner face of the T-block 69 carries a rack 72 within which cooperates a pinion 73 on the inner end of a transverse or hand operated spindle 74 suitably supported in bearings on the plate 71. Fixed on the outer end of this spindle 74 is a knob 75 and a disk 76 carrying a dial 77. This dial is suitably graduated in accordance with one or more systems of measurements desired to be used. Secured to the head stock casing by means of screws 79 and partially covering the dial 77, is a plate 80 having an indicating mark or edge 81. For the purpose of clamping the spindle 74 and the rest in any position of adjustment, a screw 82 is provided which, when tightened up, flexes the plate 80 and thereby clamps the peripheral flange 83 of the disk 76 between the plate 80 and the head stock casing. It will be understood that if the work to be engaged with the chuck is, for instance, two inches in diameter, the spindle 74 will be turned until the corresponding indication on the dial is in registry with the mark 81. The rest is now in such position that the pieces 130

of work can be successively positioned thereon for engagement with and disengagement from the chuck whether the latter is stationary or rotating.

5 The construction of the tail stock will now be described with reference to Figs. 6 to 11. The tail stock has a carriage 90 provided with ways 91 which cooperate with ways 92 of the bed A. Mounted in this carriage is a horizontally disposed shaft 93 on which the legs 94 of a tool support 95 are journaled. Slidably mounted, side by side, in the support 95 are a pair of tool holders 96, 96. In the present instance, 15 one of these tool holders carries a center drill 97 and the other a shaving tool 98. For the purpose of positioning the support 95 to bring the respective tools 97, 98 into operative position, set screws 99, 99' are provided 20 on said faces of the support for cooperation with the respective stops 100, 100' on the carriage 90. It will be understood, in the present illustrative disclosure, when the support is in that station or position 25 where the screw 99' engages the stop 100', the drill 97 is in alignment with the axis of the chuck and when the support is in its other angular station, the shaving tool is in such position as to true up the hole formed 30 by the drill.

The holders 96, 96 are connected by links 103 to a lever 104 pivoted as at 105 in a cover plate 106 of the support 95. It will be seen that when the lever is swung about 35 its pivot, one of the holders is fed forwardly and the other one is simultaneously withdrawn. The lever is also employed for rocking the tool support from one station to the other. For the purpose of preventing such 40 rocking of the support, when either of the tools are in advance position and thus prevent injury thereto which might result from rocking the head before a tool was completely withdrawn from the hole in the 45 work, a plate 101 (see Figs. 6 and 7) is provided on the carriage and this plate has a slot 102 through which the handle or lever 104 extends. The slot, intermediate its ends, has an offset portion and only when the lever 104 is in alignment with this offset can the support be rocked.

As shown most clearly in Fig. 10, the tools are held within the bores 107 of the tool holders by means of set screws 108. Pivotally secured to the forward end of each holder, as by means of a screw 109, is a plate 110 having an opening 111 of, at least, the same diameter as that of the bore 107 and also a smaller tapered opening 112. 55 When a piece of large size is to be operated upon, the opening 111 may be brought into registry with the bore 107 by turning the plate 110 on its pivot and the tool may extend forwardly some distance beyond the 60 plate 110 to take a deep cut into the work. 65

However, when the piece of work is of smaller diameter, it may be necessary to limit the extent to which the tool cuts into the work. To this end, the plate 110 is turned to the position shown in Fig. 10 from 70 which view it will be seen that the opening 112 limits the extent to which the cutting point of the tool projects beyond the plate 110 and only to that extent can the tool be fed into the work. 75

For the purpose of preventing overheating of the tools during cutting, oil or other fluid is supplied to the tools in the following manner:—115 is an oil pump (see Fig. 1) from which leads a telescoping pipe 116, 80 one end of which is carried by brackets 117 depending from the shaft 93 (see Figs. 7 and 8). This pipe communicates by means of passages 118 in one of the brackets 117 and the shaft 93 with a passage 119 in a 85 leg 94 of the support 95. The passages 119, as shown most clearly in Fig. 6, communicate by means of ports 120 with a pair of bores 121 into which telescope tubular valves 122 fixed to the rear end of the holders 90 90. The tools 97, 98 are grooved as at 123 to allow for the flow of oil to the cutting edges thereof. It will be seen that with the arrangement just described when either of the tool holders is in advance position, the 95 valve 122 connected to that holder does not cover its port 120 but the valve connected to the other holder blanks the other port 120, and thus the oil is conducted to that tool which is in cutting relation to the work 100 and the flow of oil to the other holder is shut off. It will be understood that the mere act of moving the tool holders in and out of operative position controls the flow of oil to the tools. 105

Reference will now be made to the means for accurately supporting the end of the work which is to be operated upon by the tools 97, 98. This means, in the present instance, includes a pair of work supporting 110 rollers 130 carried by slides 131 adjustably mounted in inclined grooves or openings 132 in a plate 133 connected to the forward end of the carriage 90. The carriage 90 including the plate 133 may be considered as 115 the frame of the work rest. 134 designates a hand operated spindle having right and left hand screw threads 135 in threaded engagement with traveling nuts or blocks 136 provided with inclined ribs 137 which engage in grooves 138 in the slides 131. It will be seen that upon rotation of the spindle 134 in one direction, the nuts 136 move 120 towards each other and the ribs 137 acting in the nature of wedges, cause the slides to move upwardly towards the axis on which the work is to be turned. When the spindle 134 is rotated in the opposite direction, the nuts travel away from each other and lower 125 the slides 131. Fixed to the forward end 130

of the spindle 134 is a knob 142, the sleeve of which is provided with a pinion 143 (see Fig. 6) meshing with the teeth 144 on the perimeter of a disk 145 carrying a dial 146 similar to the dial 77 heretofore described. The disk 145 is journalled on a pin 147. The plate 148, which carries an indicating mark 149, is adapted to be flexed by the screw 150 to lock the disk and spindle 134 in adjusted positions. It will be seen that when the spindle 134 is rotated to adjust the rollers 130, the extent of rotation will be indicated by the dial or scale 146, and thus the work rest rollers may be very accurately positioned in accordance with the diameter of the work so that when the work is placed on these adjusted rollers, its axis will be in precise alinement with the axis of the chuck and in proper relation to the tools as they are fed up to the work.

For the purpose of longitudinally adjusting the hand operated spindle 134, so that in any vertical position of adjustment of the work rest rollers these rollers will be symmetrically spaced with respect to the axis of the chuck, the arrangement shown most particularly in Fig. 11 is provided. As will be seen from this figure, a pair of spaced collars 153 are fixed to the rear end 23 of the spindle 134 and between these collars is interposed a portion of a member 154 mounted for adjustment in a recess 155 in the carriage 90. Carried by the member 154 is a screw 156 the head of which abuts 33 against a shoulder 157 on the carriage. Threaded into the carriage is a screw 158 the head of which engages against an abutment 159 on the member 154. Now if the spindle 134 is to be adjusted to the right, referring to Fig. 11, the screw 156 is untightened and the screw 158 is screwed up until it has moved the member 154 and the spindle 134 to the proper extent, and then the screw 156 is screwed home to hold the spindle 134 against movement to the left. If it is necessary to adjust the spindle 134 to the left, the screw 158 is untightened, the screw 156 is screwed further into the member 154 to draw the same to the left, 50 and then the screw 158 is tightened up.

For the purpose of securely holding the work against vibration, while at the same time permitting ready positioning and removal of the work from the rest rollers 130, there is provided the work holding lever, 55 shown most clearly in Figs. 8 and 9. The lever 161 carries a roller 162 adapted to rest upon the top of the work. This lever is pivoted, as at 163, on the carriage 90, and concentrically of this pivot is a fixed disk 164 with the periphery of which cooperates a friction shoe 165 pivoted as at 166 to a block 167 which in turn is pivoted as at 168 to the lever 161. The pivots of the shoe 165 and 60 the block 167 are so arranged that these

members constitute a toggle joint. 169 designates a spring pressed plunger carried by the lever 161 and normally tending to turn the block 167 in a direction to engage the shoe with the disk 164. Slidably mounted in the lever 161 and engaging at one end against the block 167 is a pin 171. Pivoted to the free end of the lever 161 is a handle 172 having a cam edge 173 for moving the pin 171 towards the block 167 when the handle 172 is lifted. It will be understood that when the lever 161 is thrown down into operative position, the plunger 169 will turn the block 167 in a direction to engage the shoe with the disk 164. The work cannot then raise the roller 162, for any force tending to raise the lever 161 only wedges the shoe more tightly against the disk 164. When it is desired to raise the lever 161 to permit of removal of the work, the handle 85 is swung upwardly on its own pivot causing the cam edge 173, acting through the pin 171, to turn the block 167 in a direction to withdraw the shoe from the disk 164 and the lever is now free to be swung into the upright position shown in Fig. 6. The extent to which the lever can be thrown back is limited by the engagement of the projection 174 against the stop 175.

The operation of the machine is briefly as follows. To set up the machine, the work rest 68 on the head stock is vertically adjusted to support one end of the work in approximate axial alinement with the chuck. The proper adjustment of the work rest 68 may, as stated, be determined by means of the scale 77. The work rest rollers 130 on the tail stock are very accurately adjusted by means of the hand operated spindle 134, in conjunction with the scale 146, so that when the work is positioned on these rollers it will be in precise axial alinement with the chuck and in proper relation with respect to the tools 97, 98. After the rests on the hand and tail stock are thus adjusted, a piece of work is placed upon these rests; the lever 161 is lowered into the position shown in Fig. 8; and the operating lever 25 is thrown to cause the chuck jaws to grip and rotate the work. The support 95 is moved into the angular station or position where the drill 97 is in alinement with the work and then the lever 144 is moved to feed the drill into the work. After the drill has operated, it is withdrawn, the support 95 is rocked to its other angular position and then the shaving tool is fed into the work. After a center is thus formed in the work, the work holding lever 161 is raised into the position shown in Fig. 6, and the lever 25 is thrown to move the shifting bar 22 in a direction to unchuck. When the lever 25 is thus thrown to unchuck, the shipper 30, in the event that the cam 57 is in the position shown in Fig. 3, is automatically released resulting in 130

throwing the power off. The piece of work may now be removed from the rests and the operation repeated on successive pieces.

I claim as my invention:-

- 5 1. In a metal working machine, a head stock including a chuck, an adjustable work rest positioned forwardly of the chuck for supporting a piece of work to be gripped thereby, means for adjusting said work rest, 10 a tail stock including a carriage, a tool carried by said tail stock for operation upon the end of the work, said tool having an operative position in axial alinement with the work, a work rest positioned on said carriage 15 forwardly of said tool, and means for accurately adjusting said second mentioned rest to support the free end of the work in alinement with the tool. 20 2. In a metal working machine, work rotating means, a support mounted for angular movement about a fixed axis, a plurality of tool holders carried thereby, a tool carried by each holder, and means for positioning said support at a plurality of stations and 25 at each of which a tool is in predetermined relation to the axis of said work rotating means. 30 3. In a metal working machine, a rotating chuck, a work rest for holding the work in axial alinement with said chuck, a support mounted for angular movement about an axis in parallelism with the axis of said chuck, a plurality of tool holders each supported for movement on a line parallel with 35 the axis of said support, a tool carried by each tool holder and equally spaced from the axis of said support, means for angularly positioning said support to bring the several tools into predetermined relation to the axis 40 of said chuck, and means for moving said holders to feed the tools to the work. 45 4. In a metal working machine, a spindle, a chuck carried thereby, an operating lever therefor, mechanism for throwing the power off of said spindle, and a connection between said lever and mechanism for releasing the latter when said lever is moved to unchuck, said connection including a longitudinally movable rod, a shoe carried by 50 said lever and frictionally engaging said rod, and a spring behind said shoe. 55 5. In a metal working machine, a spindle, a chuck carried thereby, an operating lever therefor, an element for throwing the power on and off of said spindle, means normally urging said element into off position, means for holding said element in on opposition, and a connection between said lever and last 60 mentioned means for operating the latter to release said element and thereby throw the power off when the chuck is unchucked. 65 6. In a metal working machine, a spindle, a chuck carried thereby, means for operating said chuck, mechanism actuated by said operating means when the latter is moved to unchuck for throwing the power off of said spindle, and means for preventing, at will, actuation of said mechanism when said operating means is moved. 70 7. In a metal working machine, a spindle, a chuck carried thereby, an operating lever therefor, an element for throwing the power on and off of said spindle, a spring normally urging said element into off position, a catch for holding said element in on position, and a connection between said lever and said catch for releasing the latter when the lever is moved to unchuck. 75 8. In a metal working machine, a spindle, a chuck carried thereby, an operating lever therefor, mechanism for throwing the power off of said spindle, a connection between said lever and said mechanism for releasing the latter when the lever is moved to unchuck, and means for rendering said connection inoperative at will. 80 9. In a metal working machine, a spindle, a chuck carried thereby, an operating lever therefor, mechanism for throwing the power off of said spindle, a connection between said lever and mechanism for releasing the latter when said lever is moved to unchuck and including a longitudinally movable rod, and means for preventing, at will, actuation of said rod when said lever is moved to unchuck. 90 10. In a metal working machine, a spindle, a chuck carried thereby, an operating lever therefor, an element for throwing the power off, a catch for holding said element in on position, a connection between said lever and catch for operating the latter to release said element when the lever is moved to unchuck, means for rendering said connection inoperative at will, and manually operable means independent of said lever for actuating said catch to release said element. 100 11. In a metal working machine, a spindle, a chuck carried thereby, a shiftable bar for operating said chuck, a lever for shifting said bar, a belt shifter for throwing the power on and off of said spindle, a spring normally urging said shifter into off position, a catch for holding said shifter in on position; a connection between said lever and catch including a longitudinal movable rod and a shoe carried by said lever and frictionally engaging said rod; a cam holding said rod against longitudinal movement, 115 and means for actuating said catch to release said shifter independently of said lever. 120 12. In a metal working machine, a support mounted for angular movement, a tool holder mounted for longitudinal movement therein, a lever pivoted to said support and operatively connected to said holder, and means cooperating with said lever for preventing rocking movement of said support 125 130

except when said lever is in a predetermined position.

13. In a metal working machine, a support mounted for angular movement, a tool holder mounted for longitudinal movement therein, a lever pivoted to said support, a connection between said lever and holder, and a plate fixed independently of said support and having a slot permitting pivotal movement of said lever but preventing rocking of said support except when said lever is in withdrawn position.

14. In a metal working machine, a carriage, a support mounted for angular movement therein, a pair of tool holders slidably mounted in said support, a lever pivoted to said support and operatively connected to said holders, and a plate fixed to said carriage and having a slot through which said lever extends, said slot being offset intermediate its ends to permit of rocking movement of said support.

15. In a metal working machine, a base, a tail stock adjustably mounted thereon and including a carriage, a support mounted for angular movement therein, a plurality of tool holders carried by said support, a tool in each holder, means for angularly positioning said support to bring the respective tools into operative position, and a work rest on said carriage for supporting one end of the work in proper relation to said tools.

16. In a metal working machine, a carriage, a shaft mounted therein, a support journaled on said shaft, a pair of tool holders arranged side by side in said support, a tool carried by each holder, interengaging

means between said support and carriage and to each side of said support for angularly positioning the latter to bring the respective tools into operative position, and a work rest on said carriage including means for adjusting the same.

17. In a metal working machine, a tool holder having a bore, a tool mounted in said bore, and a plate pivoted to the forward end of said tool holder and having an opening of lesser diameter than said tool for limiting the extent of projection of said tool.

18. In a metal working machine, a tool holder having a bore, a tool mounted for adjustment in said bore, and a plate pivoted to the forward end of said tool holder and having an opening of at least the same diameter as said tool so that said tool may project any desired distance beyond said plate, said plate having a second opening of lesser diameter than said tool and adapted to be brought into alinement with said bore for limiting the extent of projection of the tool forwardly of the plate.

19. In a metal working machine, a support, a pair of tool holders slidably mounted therein, a tool carried by each holder, means for simultaneously moving said tool holders in opposite directions, passages through said holders for conducting a fluid to said tools, and a valve carried by each holder, each of said valves being in open position when the tool holder with which it is associated is advanced and being in closed position to shut off the flow of fluid when the tool holder is retracted.

BENGT M. W. HANSON.
